DESIGN FOR A WEIGHING DEVICE

Ode D. Jennings, Chicago, Ill., assignor to O. D. Jennings & Co., Chicago, Ill., a corporation of Illinois

Application December 18, 1936, Serial No. 66,627

Term of patent 3½ years

To all whom it may concern:

Be it known that I, Ode D. Jennings, a citizen of the United States, and a resident of Chicago, in the county of Cook and State of Illinois, have invented a new, original, and ornamental Design for a Weighing Device, of which the following is a specification, reference being had to the accompanying drawing, forming a part thereof, and in which:

The figure is a perspective view of the weighing device showing my new design.

I claim:

The ornamental design for a weighing device, as shown.

ODE D. JENNINGS.
